UNITED STATES PATENT OFFICE.

HENRY HILD, OF BRITT, IOWA.

GRADER.

SPECIFICATION forming part of Letters Patent No. 309,543, dated December 23, 1884.

Application filed March 5, 1884. (No model.)

To all whom it may concern:

Be it known that I, HENRY HILD, a citizen of the United States, residing at Britt, in the county of Hancock and State of Iowa, have 5 invented an Improvement in Graders, of which the following is a specification.

This invention relates to that class of graders which are used to make roads by moving the earth from the ditch at each side of the 10 road to the center thereof to raise the same above the common level, or to load wagons.

The object of my invention is to plow up the earth, and to carry the same the required distance to one side of the furrow, or load it 15 into a wagon at one and the same operation.

To this end my invention consists in the construction and combination of parts, hereinafter described and claimed, reference being had to the accompanying drawings in which— 20 Figure 1 is a side elevation, Fig. 2 is a plan view, and Fig. 3 is a rear elevation, of my improved grader.

A represents the plow, secured by a vertical post, *a*, to a longitudinal beam of the main frame B of the machine. The frame B is supported on three wheels, D, E, and F. The wheel D is fixed to run in the furrow by means of a vertically-adjustable bifurcated post, *d*, in the lower end of which the wheel is journaled. The upper end of this post is pivoted 25 to a lever, *e*, which is in turn pivoted to the frame B, and the middle of the post passes through the frame. By means of lever *e* the post *d* and wheel D may be pressed upon, so 30 as to raise the frame B and take the plow out of the ground.

e' is an arc attached to the frame, and provided with pin-holes, into which a pin may be inserted above or below lever *e*, either to 35 hold the wheel up from the ground, so that the plow may be guided as to the depth of its furrow without the assistance of wheel D; or the wheel may be set just as low as the plow to assist the latter in supporting frame B; or 40 the wheel may be thrust low down to support the frame and carry the plow above ground. The wheel D' is mounted in a swinging yoke, *b*, which is pivoted at its rear end to the frame B, and at its forward end to a lever, *b'*, which 45 is fulcrumed at *c* on a stud erected on frame 50

B. This wheel D' is to run on top of the ground ahead of the plow, and by raising or lowering it the depth of the furrow may be gaged. The lever *b'* is held at any desired elevation by a brace, *c'*, having pin-holes in 55 it, and a pin adapted to pass through said holes and through the lever *b'*.

E is a caster-wheel supporting the forward part of the frame.

F is a large drive-wheel, made rough on its 60 circumference to engage the ground to insure the wheels turning when the machine is hauled along. This wheel F is journaled in a yoke, *f*, which is pivoted to the frame B at *f'*, concentric with a shaft, G. The drive-wheel F 65 is provided with a circle of gear-teeth, *g*, which engage a pinion, G', on shaft G.

H is a beveled gear-wheel secured on shaft G, engaging another beveled wheel, *k*, on shaft *h*.

I is an endless apron of slats secured together by hinge-joints, as hereinafter described, to travel as a belt around the cylinders *i i'*. The cylinder *i'* is carried very close to the ground, and close to the mold-board of the plow, to receive the earth turned up thereby upon the apron. The lower end of the frame I', supporting the cylinders *i i'*, which carry the apron, is supported by hangers *i''*, depending from the frame B. The middle portion of the frame I' 75 rests upon the main frame B, and it may be vertically adjustable to set the roller *i'* high or low.

When the grader is used for grading only, the frame I' will lie at a very slight inclination 80 to a horizontal plane, and will be made to extend beyond the main body of the grader as far to one side as may be desired.

When the grader is used for loading wagons, the frame I' will be sufficiently elevated 85 at its outer end to carry cylinder *i* over the wagon alongside, thus enabling the apron I to continually dump its load into the wagon. The frame I' is thus a lateral extension of the main frame B. The apron is 90 rotated by means of a chain, J, running from a rag-wheel on cylinder *i* to a rag-wheel, K, on the shaft *h* of a beveled gear, *k*, which engages another beveled gear, H, on shaft G, carried by pinion G', thus engaging with the 95 100

drive-wheel F. When the machine advances, the plow turns a furrow of earth onto the apron, which dumps it to one side, or into a wagon hauled alongside, as desired.

5 *l* is a cross-beam secured to the end of the team-pole M, for the double purpose of securing the forward team in proper line of draft at *m*, and to haul the plow by means of the connecting rod or chain N. The first team of 10 three horses is secured to a draft-rod, *n*, by means of peculiar equalizing-whiffletrees.

15 *O* is the double-tree made in duplicate parts, one above the other, admitting the equalizing-bars *o* between its parts. The equalizing-bars *o* are pivoted one-third their length from their outer ends to the double-tree. On the outer end of each bar *o* is hung a single-tree or whiffletree, P, for one horse each. On the inner ends of both bars *o* is hung another whiffletree, P', for one horse to pull against the two outside horses. By this means the strain is 20 more direct than by the old style of three-horse gear. A forward team may be secured by the same style of gear to the frame at *m*. 25 The frame B is raised or lowered relative to the axle of wheel F by means of a rope or chain, R, wound upon an axle, *r*, by cranks S, the rope passing around a pulley, T, on the frame B, and under another pulley, *t*, on 30 an arm of said frame, thence upward to the yoke *f*, to which it is secured. By turning cranks S one way the rope R will be wound onto shaft *r*, and will draw the frame B at pulley *t* up toward yoke *f*, and vice versa, the 35 frame B swinging upon the other wheels, D D' E, and upon the pivot *f'* of yoke *f*. Either of the cranks S may be pushed through the crank-lever into the frame B, to retain the crank at any desired point, and thus hold the frame 40 elevated.

45 *V* is a seat for a driver. This seat is supported over the apron on rods extending to the frame B. It is thought that earth may by means of this device be very much more rapidly moved away from the plow which

loosens it than by any method of scraping said loosened earth along the ground, inasmuch as the friction of my carrier-apron, revolving upon small journaled cylinders, is less than the friction of any scraper carrying the same 50 load over rough ground; also, this means of elevating the earth into a wagon alongside is strictly mechanical, and a great advantage in supplementing manual labor by machinery and animal labor. The hinge-joints of the 55 endless apron I travel on rag-wheels on cylinders *i i'*. Each slat of the apron I is hung to the side chains or hinges by means of projecting tongues *s'*, attached to one side of one edge of each slat, leaving the other edge of 60 the slat free to swing loose when it is in the lower half of its circuit, so that any dirt that may have got between the belt may be free to drop out.

What I claim as my invention, and wish to 65 secure by Letters Patent, is—

1. The combination, with the earth-moving device, comprising the plow A, the belt I, and the driving mechanism described supported upon frame B, of the team-connecting rod *n*, 70 and the beam or pole M, secured to said frame B, the cross-beam *l*, secured to pole M, the team-hitch *m*, attached to beam *l*, and the stay-rod N, connecting the end of said beam with the frame B, substantially as shown and de- 75 scribed.

2. The combination, with a grader-frame provided with a plow and means for carrying laterally therefrom the earth turned up thereby, of a drive-wheel hung in a vertically-adjustable yoke to said frame, a rope or chain attached to said yoke and passing around pulleys on the frame, and means for winding said rope and securing it, whereby the frame may be elevated relative to the yoke and held at 80 85 the height desired, as specified.

HENRY HILD.
